E. HORN.
ARTICLE HOLDER.
FILED JULY 22, 1922.

UNITED STATES PATENT OFFICE.

ELLWOOD HORN, OF PHILADELPHIA, PENNSYLVANIA.

ARTICLE HOLDER.

Application filed July 22, 1922, Serial No. 576,724.

To all whom it may concern:

Be it known that I, ELLWOOD HORN, a citizen of the United States, residing at Philadelphia, in the county of Philadelphia and 5 State of Pennsylvania, have invented certain new and useful Improvements in Article Holders, of which the following is a specification, reference being had to the accompanying drawings.

10 This invention relates to holding devices, and has for its object to provide a holder capable of supporting a number of articles within convenient reach of the user.

15 It is another object of the invention to provide a holder of this character capable of use as an advertising medium and arranged to support articles such as a telephone directory or memorandum book.

20 It is a further object of the invention to provide a holder of this character capable of being formed from a blank of material, said holder not only including means for supporting an article, but also means for supporting the holder.

25 With these and other objects in view, the invention consists in the improved construction and arrangement of parts to be herein-after more particularly described, fully claimed and illustrated in the accompanying 30 drawings, in which:—

Figure 1 is a perspective view of an article holder constructed in accordance with an embodiment of the invention;

Figure 2 is a side elevation showing the 35 device applied to a wall;

Figure 3 is a rear elevation of the structure shown in Figure 1;

Figure 4 is a plan view of the blank before the holder is assembled;

40 Figure 5 is a detailed view of one form of fastening means; and

Figure 6 is a detailed view of another form of fastening means.

Referring to the drawings, 5 designates a 45 blank of material including a relatively large central portion 6. One end portion of the blank is reduced to provide an arm 7 having an opening 8 in the end portion thereof. The opposite end portion of the blank 50 is also reduced to provide an arm 9 having an opening 10 in the end portion thereof. The arm 9 is shorter than the arm 7. This is caused by enlarging the portion 11 of the blank between the central portion 6 and the 55 arm 9.

The purpose of the enlarged portion 11 is

to permit a supporting arm 12 to be struck therefrom, the supporting arm 12 having a relatively large opening 13. After the arm 12 has been struck from the portion 11, sufficient metal is left to properly reinforce or connect the arm 9 to the central portion 6 of the blank. When the blank has been stamped as above described, the same is bent on the line a—a so as to position the arms 7 and 9 65 in spaced relation, with the extremities of said arms in parallel relation.

It will be noted that by bending the arms on the line a—a that the portion from said line to the extremity of the arm 7 is longer 70 than the portion of the blank from the line a—a to the extremity of the arm 9. This permits the arm 9 which includes the portion 11, with the exception of the arm 12, to be disposed substantially flat, so as to engage 75 a wall or like support. The remaining portion, that is, the central portion 6 and the arm 7, is curved outwardly and downwardly as at 14 so as to position the enlarged central portion 6 on an incline. This portion 80 6 is made relatively broad so that advertising matter may be printed or applied thereto.

In assembling the holder, the arm 12 is extended substantially upwardly at an inclination to the arm 9, the opening 13 of the arm 12 being adapted to engage a hook A or like supporting means carried by the wall. By bending the material in the manner described, the arms 7 and 8 will naturally be disposed in divergent relation to each other, 85 in view of the resiliency of the blank. In order to draw the arms to each other, fastening means is provided, said means extending through the registering openings 8 and 10, 90 so as to bridge the space between said arms and draw said arms toward each other.

This fastening means may be in the form of a bolt 15 having a nut 16 on one end thereof, as shown in Figure 2. It may also be a 100 threaded sleeve 17 having a screw 18 engaged therewith, the end portion 19 of the screw being enlarged, or corresponding in diameter to the diameter of the sleeve 17, as shown in Figure 5. The fastening means 105 may also be in the form of a threaded sleeve 20 having a head 21, said sleeve being relatively long and adapted to receive the shank of a screw 22, as shown in Figure 6.

This holder is an excellent device as an 110 advertising medium, as the central portion 6 is not only disposed at an inclination so as

to be easily observed by anyone when the device is hung upon a wall, but is relatively broad so that any quantity of advertising matter may be applied to said portion.

5 As shown in Figure 3, the central portion 6 renders the portion 11 and the opening caused by the arm 12 invisible. As the formation of the portion 11 at the junction of said portion with the arm 9 coincides with 10 the central portion 6 at the junction of said portion with the arm 7, the device is rendered neat in appearance. In addition to this, a novel supporting arm is provided, without requiring using the central or large 15 portion 6 of the blank intended for advertising matter. The fastening means is intended to support a telephone directory, city directory, catalog, or like devices by passing the fastening means through the usual opening found in such books, so as to position the book within convenient reach of the operator. By the gradual curvature of the arms 7 and the central portion 6, a 20 relatively large compartment is formed between the arms 7 and 9 so that it is possible to extend the book upwardly and partially inwardly of the frame, to permit the user to turn the pages of the directory without removing the holder from the book or from 25 the wall. It will also be found exceedingly useful as a bill holder, card holder, or for 30 memorandum sheets.

From the foregoing it will be readily seen that this invention provides a novel form of holder which is capable of holding any book of a thickness corresponding to the length of the fastening means, regardless of the weight of the book, as there are no pivots or like separate parts to come unfastened. In addition to this, the devices 35 40 may be stamped in large numbers from a small quantity of sheet metal, and in view of the blank formation of the holder it is an easy matter to apply any form of advertising matter to the central portion 6 of the 45 holder before the holder is assembled. All of these features are possessed by a device having unlimited utility.

What is claimed is:—

As an article of manufacture, an article 50 holder consisting of a single sheet of metal cut to provide a relatively large central portion and relatively narrow arms at its ends, said arms being disposed substantially in parallel relation to each other, means connecting the ends of said arms to each other, the central portion of said sheet having an integral supporting tab cut out of the material and struck up, the tab having an 55 60 opening.

In testimony whereof I hereunto affix my signature.

ELLWOOD HORN.
